PAINTER'S ACCESSORY

Einer F. Hansen, Highland Park, Mich.

Application May 11, 1945, Serial No. 593,305

2 Claims. (Cl. 211—65)

1

This invention relates to painters' accessories and has particular reference to a combined strainer and brush supporting mechanism.

An object of the invention is the provision of a device which is adapted to be applied to a paint can, whereby a paint brush may be supported thereon temporarily during painting operations or stored permanently in position to prevent the brush from drying out.

Another object of the invention is the provision of a device which may be applied to a paint can, whereby excess paint may be removed from a paint brush during painting operations.

The foregoing objects and other advantages of the invention will become more apparent as the description proceeds, reference being made from time to time to the accompanying drawings forming part of the within disclosure, in which said drawings:

Fig. 1 is a perspective view of a device embodying my invention.

Fig. 2 is a view similar to Fig. 1 with the brush rack in extended position for permanently supporting one or more brushes.

Fig. 3 is a side elevation of the device illustrated in Fig. 1.

Fig. 4 is a fragmentary detail showing the manner in which the brush supporting rack is mounted.

Fig. 5 is an enlarged fragmentary detail showing an end portion of the device illustrated in Fig. 1.

Fig. 6 is a perspective view of a paint can with my improved device in position thereon, and illustrating the manner in which excess paint may be removed from a brush.

Fig. 7 is a perspective view of a paint can showing the brush rack in extended position, whereby a plurality of brushes may be supported with their bristles suspended in the paint to prevent too rapid drying.

Fig. 8 is a perspective view of a paint can equipped with my improved device and illustrating the manner in which the same may be utilized as a paint strainer.

Fig. 9 is a perspective view of a paint can with my device in position to temporarily support a paint brush during painting operations.

Referring now more particularly to the drawings, it will be understood that in the embodiment herein disclosed, my improved device consists of an arcuate body member 11 which may be made of a metal, plastic, or other suitable material and which is provided with a rolled edge 12 terminating in a depending flange 13 adapted to

2

fit over the rim of a paint can as illustrated in Figs. 6, 7, 8, and 9.

The body member 11 is provided with a concave central area 14 which is perforated as at 15, and which serves as a paint strainer, and which permits excess paint to return to the interior of the paint can when a paint brush is temporarily supported on the device. The inside edge 16 of the body member 11 is downwardly inclined to provide a scraper for removing excess paint from a brush during painting operations.

At either side of the body member 11 ears 17 and 18 are upwardly bent to provide bearing members for the brush rack 19. The brush rack 19 is preferably made of a heavy wire bent and rebent as shown in Figs. 1 and 2 to provide resilient grips as at 20 for the insertion of one or more paint brushes.

The ends of the rack 19 are inserted through 20 suitable apertures in the ears 17 and 18, and are bent and rebent as shown in Figs. 1, 2, and 4 so that the rack 19 may be swung into retracted position as shown in Fig. 1, and into extended position as shown in Fig. 2.

The ends 21 and 22 of the rack 19 serve as stops 25 adapted to engage the under side of the body member 11, Fig. 2, to maintain the rack 19 in horizontal position when the rack 19 is employed to support the brushes on the interior of the can.

When it is desired to use the device as a temporary support, Fig. 9, for the paint brushes during painting operations, the rack 19 is folded back into retracted position as shown in Figs. 1, 6, and 9, in which position it is out of the way so that the interior of the paint can may be reached and the scraper edge 16 may be employed by the painter.

When it is desired to use the device as a paint strainer, the rack 19 may be extended as shown 40 in Fig. 2, and when it is desired to employ the device as a permanent support for a plurality of paint brushes as shown in Fig. 7, the rack 19 is swung in extended position as shown in Fig. 2 so that the brushes may be hung in a vertical 45 manner with their bristles extending into the paint.

It will be seen by the foregoing description that I have disclosed a novel device which has many 50 applications and uses in the painting trade.

Having described my invention, what I claim and desire to secure by Letters Patent is:

1. In a device of the character described, an arcuate body portion having a rolled edge adapted to be supported over the edge of a paint can, a concave central portion having a plurality of

apertures therein, and a brush rack comprising a wire bent and rebent upon itself, pivotally mounted on said body portion.

2. A perforated concave body member having an arcuate edge adapted to be press fitted over the edge of a paint can, upwardly extending ears on said body member, and a brush rack, comprising a wire bent and rebent upon itself, pivotally mounted on said ears.

EINER F. HANSEN.
